UNITED STATES PATENT OFFICE.

WESLEY EMIL BOHN, OF CORTICANA, TEXAS.

ICE-COLD ICE BOX.

Application filed November 2, 1925. Serial No. 66,337.

To all whom it may concern:

Be it known that I, WESLEY EMIL BOHN, a citizen of the United States, residing at Corsicana, in the county of Navarro and 5 State of Texas, have invented a new and useful Ice-Cold Ice Box, of which the following is a specification.

This invention aims to provide a novel 10 form of ice-cold ice box in which the water derived from melting ice may be used to cool bottled drinks, and for other purposes.

In the drawings:—Figure 1 shows in vertical longitudinal section, an ice-cold ice box constructed in accordance with the invention; Figure 2 is a transverse section; Figure 3 is a section on the line 3—3 of Figure 1; Figure 4 is an elevation showing a modification, parts being broken away; Figure 5 is an elevation showing a portion of 20 an ice-cold ice box constructed in accordance with the invention.

The ice-cold ice box forming the subject matter of this application comprises a box-like body 1 which may be supported on legs 2 or otherwise, the body 1 being provided at 25 its upper end with an internal shoulder 3 on which rests the horizontal flange 4 of a tray 5, the flange 4 being disposed at the upper end of the vertical wall 6 of the tray, 30 the tray, thus, being supported removably in the body 1 of the ice-cold ice box. In the central portion of the tray 5 is located a container 7 for ice. The tray 5 has longitudinal partitions 8 disposed at the sides of 35 the ice container 7, and between the longitudinal partitions 8, at the ends of the container 7, are located transverse partitions 9. The construction of the ice-cold ice box is such that the tray 5 embodies the container 40 7, longitudinal compartments 10 at the sides of the container, and transverse compartments 11 at the ends of the container, between the longitudinal compartments. The bottom of the transverse compartments 11, 45 marked by the numeral 12 is disposed at a lower elevation than is the bottom 14 of the longitudinal compartments 10. In the sides of the container 7 there are openings 15 which communicate with the longitudinal 50 compartments 10, the lower edges of the openings 15 being flush with the bottoms 14 of the longitudinal compartments 10. There are openings 16 in the longitudinal 55 partitions 8, the ends of the container 7 having openings 17 disposed flush with the bottom 12 of the transverse compartments 9,

The transverse partitions 9 have openings 18. The container 7 is surmounted by a removable lid 19.

The construction of the ice-cold ice box 60 is such that when a chunk of ice is placed in the container 7, and when the ice melts, the water from the melting ice will pass through the openings 15 of the container 7, and through the openings 16 of the longitudinal partitions 8 into the longitudinal compartments 10. Similarly, the water from the melting ice will pass through the openings 17 in the ends of the container 7, into the transverse compartments 11, and be distributed through the said compartments by 65 way of the openings 18. Outlet pipes 20, located as desired, are mounted in the bottom 12 of the longitudinal compartments 10. The outlet pipes 20 upstand at a considerable 70 distance above the upper edges of the partitions 8 and 9. The result is that ice water stands at a fixed depth in the compartments 10 and 11, the water standing at a greater depth in the compartments 11 than 75 it does in the compartments 10 because, as shown in Figures 1 and 2, the bottom of the compartments 11 is lower than the bottom of the compartments 10. The water, thus, is of different depths in the compartments 10 80 and 11, shorter bottles being disposed in the compartments 10, and longer bottles being disposed in the compartments 11.

The water, flowing downwardly through the pipes 20, accumulates in the bottom of 85 the body 1 of the ice-cold ice box and stands at a level determined by an outlet pipe 21 mounted in the bottom of the body 1 and equipped at its lower end with a water sealing device 22.

Partitions 23 extend longitudinally of the body 1 of the ice-cold ice box, in the bottom thereof, and are provided with openings 24, so that the water in the bottom of the ice-cold ice box can find its way to the outlet pipe 100 21. The partitions 23 support a shelf 25, of any desired construction, the shelf being located above the water level as determined by the pipe 21. Provisions may be placed on the shelf 25, and will be kept cool and 105 dry. In the water which accumulates in the body 1, milk bottles or the like may be placed, on opposite sides of the partitions 23.

A top 26 rests on the body of the ice-cold 110 ice box and has a downwardly extended portion 27 extended into the upper end of the body 1 and engaging the flange 4 of the tray

5. Doors 28 are hinged to the top 26, and may be opened to permit the insertion of ice into the container 7, and also to give access to the bottles which are located in the compartments 10 and 11. The front of the body 1 of the ice-cold ice box has one or more hinged doors 29 giving access to the space below the tray 5.

In Figure 4 of the drawings, the body of 10 the ice-cold ice box is marked by the numeral 30, and the tray is shown at 40. The body 30 of the ice-cold ice box has a false or elevated bottom 31, which may be omitted if desired. The outlet pipe, corresponding to 15 the pipe 20, is designated by the numeral 32. The modification shown in Figure 4, consists essentially, in the omission of the partitions 23 and the shelf 25 of Figures 1 and 2.

The device, generally considered, is so 20 constituted that it will keep bottles of liquid cool and properly submerged, the water derived from melting ice being made use of, whereas, at present, the water from the melting ice is permitted to run away idly, no ad- 25 vantage being taken of the cooling properties of the ice water.

On any portion of the article may be placed a characteristic mark, as shown at 50 in Figure 5, the said mark embodying concentric circles 51 within which is shown 30 a conventional representation of a bottle, indicated at 52, with the words "Ice-Cold", as shown at 53. Either the bottle disclosed at 52, or the circles disclosed at 51, or both, may be omitted if desired, but I consider 35 it highly important that the words "Ice-Cold" appear prominently in this patent application.

What is claimed is:—

In a device of the class described, a body, 40 a tray in the body, an ice container in the tray, longitudinal partitions in the tray at the sides of the container, transverse partitions in the tray at the ends of the container, the partitions defining side compartments 45 and end compartments, the bottoms of the side and end compartments being disposed at different elevations, and the container having openings communicating with the compartments.

WESLEY EMIL BOHN.
